HENRY SCHILD AND GEORGE J. PRENTICE, OF NEW YORK, N. Y., ASSIGNEES TO
GEORGE J. PRENTICE; SAID PRENTICE ASSIGNEE TO LEWIS PRENTICE, OF NEW
YORK CITY.

Letters Patent No. 98,890, dated January 18, 1870; antedated January 10, 1870.

IMPROVEMENT IN CIGAR-MACHINES.

The Schedule referred to in these Letters Patent and making part of the same.

To all whom it may concern:

Be it known that we, HENRY SCHILD and GEORGE J. PRENTICE, of the city and State of New York, have invented and made a certain new and useful Improvement in Cigar-Machines; and we do hereby declare the following to be a full, clear, and exact description of the said invention, reference being had to the annexed drawing, making part of this specification, wherein—

Figure 1 is a plan of the machine.

Figure 2 is a section of the same, transversely of the rollers.

Figure 3 is a section of the tip-die.

Figure 4 is an elevation of the screw-clutch and lever.

Figure 5 is a plan, and

Figure 6, an elevation of a variation of the screw-clutch and lever.

Similar marks of reference denote the same parts.

This invention is designed to facilitate the construction of the cigar-machine, lessen its cost, increase the durability, and allow the same machine to be employed in making the bunches, or in putting on either a right or a left-hand wrapper, and completing the cigar, including the conical tip.

We are aware that cigar-machines have before been made, in which four rollers have been employed to roll the cigar, and put on the wrapper, and form the tip, and that to one of the rollers an end-motion has been given, so as to force the cigar either way into the tip-die.

The nature of our said invention consists in an eccentric bearing for the back upper roller, and the frame that carries the forward upper roller, so that by the act of moving the frame, to raise the front upper roller, the rear upper roller will be carried back by its eccentric bearings, so as to liberate the cigar, and give room for introducing the next bunch or filler.

We also make use of a shaft, with a right and left screw cut upon it, and use a movable tooth or rack, that is placed so as to take either one screw-thread or the other, and give end-motion to the roller in one direction or the other, and said rack can be placed so as not to touch either screw, and thereby the machine is adapted to making bunches, as well as putting on the wrappers, as aforesaid.

In the drawing—

a is part of a table or support for the machine.

b b', the side frames, connected by the bolt *c*.

d, e, f, and g, are the rollers, having India-rubber or other surfaces; and the shafts of these rollers carry pinions outside the frame *b'*, that are driven by the central pinion *h*, fig. 1. Two of these pinions, *i* and *k*, are shown in fig. 1.

The shaft *f'*, of the roller *f*, is set in the frame that

is formed by the side pieces *l* and cross-bar *m*, by which they are united.

This frame is made with large circular trunnions, entering corresponding holes in the frames *b b'*, so that this frame can be swung on these trunnions, and the roller *f*, lifted as shown by the red lines, fig. 2, and through these trunnions the shaft *g'*, of the roller *g*, passes; but said shaft does not pass through the centre of these trunnions, but eccentric thereto, as seen in fig. 3; hence, we term these trunnions the eccentric bearings *o*, for the frame *l l m* and shaft *g'*.

It will be understood, by reference to figs. 2 and 3, that the act of swinging up the roller *f* throws back the roller *g*, in consequence of the eccentricity of the bearings *o*, so that the finished cigar or bunch is liberated.

The frame *l l m* is moved by a treadle, connected directly to the bar *m* by a rod, *m²*, as in fig. 2, or to an arm, *m¹*, as in fig. 1.

The die that is used for forming the tip of the cigar, is made in two parts. The lower portion, *n*, is united with the table *p*, upon which the leaf is laid, care being taken that the parts are smooth at the points of union; and to facilitate this, and stiffen the edge of the bed next the roller *e*, a thin plate of steel may be attached, as shown in fig. 2.

The upper part, *r*, of the die is made with a joint at *z*, and a spring, *s*, is employed below the bed *p*, acting against a knuckle of the joint, to keep the die closed, but allow of the same being opened; and in order to give additional yielding pressure on the die, in forming the tip, the spring *s* is employed, the same projecting from the frame *l*.

Dies like those just described are to be employed at each side of the machine, so that the cigar can be made with a wrapper from either half of the tobacco-leaf, the end-motion of the roller *g*, that presses the cigar into the tip-die, being derived from the right and left-handed screw, as next described.

Upon one end of the shaft *g'*, right and left-hand screws are cut, the same intersecting, as seen at *s*, and a tooth is employed to take the screw, and cause end-motion, by the rotation of said roller and screw.

In figs. 1 and 4, we have shown the clutch *t*, on the screw *6*, with the teeth *7* and *8*, and spring-catch *u*. When the tooth *7* is engaged in the screw, the roller will be forced in one direction, and when the lever and clutch *t* are turned so that the tooth *8* takes the other thread of the screw, the roller will be moved the other way. The turning of the eccentric bearing in opening the rollers, disconnects the screw from the clutch, and allows one of the springs, *9* or *10*, to slide the roller and shaft endwise in its bearings, and through the pinion *i*.

The springs 9 and 10 are bent, so as to reverse the movement of the shaft, according to which screw is used, one spring, when set in the eye 20, moving the shaft one way, and the other spring, when introduced in the eye instead, giving the other direction of motion.

We prefer the button *v*, figs. 5 and 6, which can be moved by the lever *v'*, to stand at either angle, and take one screw-thread or the other.

The spring-catch *v*' serves to hold the button in either position. The spring around the shank of the button presses it to the groove, and prevents injury, if the rib of the screw takes the button before passing into the groove. The button can be drawn back, so as not to touch the screw, and the stud *w* serves to hold the same, by taking the surface of the socket in which the shank slides.

What we claim, and desire to secure by Letters Patent, is—

1. The frame *l l*, with the eccentric bearings *o o*, in combination with the rollers *g f e d*, as and for the purposes set forth.

2. The tip-die, made of two parts, and hinged, in combination with the rollers, to revolve the cigar, and a spring, to press said die together, substantially as set forth.

3. The shaft *g'* of the roller *g*, formed with right and left-hand screw-threads, in combination with the button or clutch, that can be engaged with either screw-thread, substantially as and for the purposes specified.

In witness whereof, we have hereunto set our signatures, this 20th day of April, 1869.

HENRY SCHILD.
GEO. J. PRENTICE.
